UNITED STATES PATENT OFFICE.

WILLIAM SULLIVAN, OF CINCINNATI, OHIO.

FEEDER FOR PRINTING-PRESSES.

SPECIFICATION forming part of Letters Patent No. 650,959, dated June 5, 1900.

Application filed August 2, 1899. Serial No. 725,893. (No model.)

To all whom it may concern:

Be it known that I, WILLIAM SULLIVAN, a citizen of the United States, residing at Cincinnati, in the county of Hamilton and State 5 of Ohio, have invented a new and useful Feeder for Printing-Presses, of which the following is a specification.

This invention relates to an improved feeding device for printing-presses; and it has for 10 its object to provide a device of this character specially designed as an attachment for envelop-printing machines to feed open-flap envelopes to the printing mechanism.

Heretofore in the operation of automatic 15 presses, especially of the type known as the "Harris envelop-press," a form of which is shown in the patent to Harris *et al.*, No. 577,405, issued February 16, 1897, no provision has been made for feeding the envelopes with the 20 flap open, and the flap has been utilized to receive within the fold thereof a feeding spring or blade, which serves to move the envelop to the carrying mechanism for delivering the same between the type-carrying and 25 impression cylinders. This operation is open to a number of objections, one of which is that the envelopes to be printed are stacked or piled with their flaps folded and are passed to the printing mechanism in this condition,

30 sometimes causing the sticking of the flaps to the body of the envelop, besides making it impossible to print both upon the main portion and flap of the envelop without running the same two times through the press. Furthermore, in a great many instances, especially in coin-envelops, the envelopes are constructed with the flaps unfolded or open to facilitate the handling of the envelop by the user, and by providing means for feeding an 35 envelop in this condition to the printing mechanism the objections to the ordinary feeding operation are overcome, besides permitting of both the body portion and flap being printed at one and the same operation.

40 To this end the invention contemplates a feeding device adapted to replace the usual feeding device of the Harris or similar envelop-machines and so constructed as to provide simple means for feeding open-flap envelopes to the printing mechanism.

With these and other objects in view, which will readily appear to those skilled in the art

as the nature of the invention is better understood, the same consists in the novel construction, combination, and arrangement of 55 parts hereinafter more fully described, illustrated, and claimed.

The essential features of the invention are necessarily susceptible to some modification without departing from the spirit or scope 60 thereof; but the preferred embodiment of the same is shown in the accompanying drawings, in which—

Figure 1 is a perspective view of a portion of a Harris automatic envelop-printing machine, showing the same equipped with a pair of feeding devices constructed in accordance with the present invention. Fig. 2 is a detail in perspective of one of the improved feeders or feeding devices. Fig. 3 is a longitudinal sectional view thereof, showing in dotted lines the relation which the feeder bears to the open-flap envelop when engaging with the latter to carry it from beneath the stack or pile to the carrying mechanism 75 of the press.

Like numerals and letters of reference designate corresponding parts in the several figures of the drawings.

Referring particularly to the drawings, the 80 numeral 1 designates a portion of a Harris envelop and card printing machine of the type shown in the aforesaid patent to Harris *et al.*, No. 577,405. This machine is provided, contiguous to and at one side of the type-cylinder 2, with the usual envelop magazine or holder 3, of skeleton formation and essentially consisting of a plurality of uprights 4, sustained in position by the usual collars 5, carried by the adjustable supports 6, held 85 above the machine-framework. The said uprights 4 are grouped in the usual rectangular arrangement to provide a magazine or holder of approximately this shape, so that the same will receive therein the stack or pile of envelopes, such stack or pile being designated in the drawings by the reference-letter E. Ordinarily in printing-machines of the type shown in Fig. 1 of the drawings the envelopes E are stacked together with their flaps folded, 90 as no provision is made for feeding the same with open flaps; but in carrying out the present invention the envelopes are stacked or piled within the magazine or holder with their 95 100

flaps left open, so as to obviate the objections to running a closed-flap envelop through a printing-press, as well as permitting of having both the main portion and flap of the envelop printed upon at one operation should this be desired.

In adapting the envelop-printing machine for feeding the open-flap envelops there-through it is simply necessary to replace the ordinary feeding fingers or blades, such as shown in the patent to Harris, No. 586,490, dated July 13, 1897, by the feeders forming the subject-matter of the present application. A pair of these feeders is usually associated with the feed-bar 7 of the machine to provide for carrying the envelops into the machine perfectly straight, and, being duplicates, a description of one will suffice for both.

Each feeder or feeding device (designated 20 in its entirety by the numeral 8) essentially comprises an attaching-block 9, a straight supporting-blade 10, and a longitudinally-curved feed-arm 11. The attaching-block 9 of the feeder is provided with a notch or bifurcation 12, receiving the feed-bar 7 of the machine and permitting of the adjustment of the feeder longitudinally thereof, according to the width of the envelop to be fed through the machine, and said attaching-block 9 has 25 fitted thereto a set-screw 13, working in a threaded opening at one side of the notch or bifurcation and adapted to impinge on the feed-bar 7 to hold the feeder thereon in any adjusted position. At this point it may be 30 observed that the feed-bar 7 is reciprocated in the usual manner and by the ordinary operating connections, which, forming no part of the present invention, are not illustrated in the drawings.

40 The straight supporting-blade 10 of each feeder is adapted to work over the table beneath the stack or pile of envelops within the magazine or holder, and while not acting in the capacity of a feeding medium forms a 45 partial support for the envelops and assists in holding the envelop in proper shape while being fed to the printing mechanism. Said supporting-plate 10 preferably consists of a straight strip of spring metal and is provided 50 at one end with a longitudinally-disposed slot 14, receiving the adjusting-screws 15, which engage in threaded openings in the attaching-block 9 and provide for a longitudinal adjustment of the blade 10 and its attached feed- 55 ing-arm 11 to adapt the feeder for different sizes of envelops. The arm 11 consists of a strip of spring-steel and is rigidly joined to the attached end of the supporting-blade, as at 16, so as to leave the other end thereof free 60 to enter the pocket of the envelop to provide for advancing the same toward the printing mechanism. The spring feed-arm 11 overlies the blade 10 and is disposed within the longitudinal plane thereof, but is preferably 65 of a materially-narrower width to facilitate its engagement with the envelop. Further, the said spring is curved outwardly or up-

wardly from the blade, so that it will readily spring into position for entering the pocket of a succeeding envelop when the feeder re-tires from the envelop last fed to the printing mechanism.

In the operation of the machine the pair of feeders or feed devices embodying the present invention work beneath the stack or pile 75 of open-flap envelops E, which have their flaps F disposed at the outer side of the magazine or holder, so that as the feeders are reciprocated beneath the envelops the spring feed-arms 11 thereof will readily pass beneath the flap of the lowermost envelop and enter the main pocket of the latter, so that as the feeders continue to advance the envelop will be advanced to the point where it is caught by the usual carrying mechanism 85 for delivering the same to the printing mechanism. Upon the retirement of the feeders from the envelop last fed the outward movement of the feed-bar is regulated to carry the spring feed-arms 11 to a position beneath the 90 flap of the next envelop, so that the next advance movement will carry the feed-arms into the pocket of the envelop, as before.

From the foregoing it is thought that the construction and operation and the many advantages of the herein-described feeding device will be readily apparent to those skilled in the art without further description, and it will be understood that various changes in the size, shape, and proportion and minor details of construction may be resorted to without departing from the spirit or sacrificing any of the advantages of the invention.

Having thus described the invention, what is claimed is—

1. A device for feeding open-flap envelops to printing-presses, comprising a supporting-blade adapted to extend beneath the body of the envelop, and a feed-arm overlying the said blade, and arranged to enter within the envelop, substantially as set forth.

2. A device for feeding open-flap envelops to printing-presses, comprising a support carried by the usual feed mechanism, a straight supporting-blade adapted to extend beneath the body of the envelop, and a spring feed-arm disposed at one side of the supporting-blade and arranged to lie beneath the open flap, so as to enter the pocket of the envelop, substantially as set forth.

3. A device for feeding open-flap envelops to printing-presses, comprising a support adapted to be carried by the usual feeding mechanism, a straight supporting-blade for the body of the envelop, and a separate curved feed-arm arranged at one side of, and movable with, the supporting-blade, said curved feed-arm being adapted to work beneath the open flap and into the pocket of the envelop, substantially as set forth.

4. A device for feeding open-flap envelops to printing-presses, comprising an attaching-block, a straight supporting-blade for the body of the envelop adjustably connected at

one end to the block, and a short spring feed-arm arranged within the longitudinal plane of said blade and joined to the attaching end thereof, said feed-arm having its free end 5 curved outwardly from the blade and adapted to spring into position beneath the open flap for entering the pocket of the succeeding envelop, substantially as set forth.

In testimony that I claim the foregoing as my own I have hereto affixed my signature in the presence of two witnesses.

WILLIAM SULLIVAN.
